UNITED STATES PATENT OFFICE.

MARK W. PATTEN, OF SOMERVILLE, MASSACHUSETTS.

ATTACHMENT FOR BOTTLING-MACHINES.

SPECIFICATION forming part of Letters Patent No. 226,927, dated April 27, 1880.

Application filed January 27, 1880.

To all whom it may concern:

Be it known that I, MARK W. PATTEN, of Somerville, county of Middlesex, and State of Massachusetts, have invented a certain new and useful Improvement in Attachments for Bottling-Machines, of which the following is a description sufficiently full, clear, and exact to enable any person skilled in the art or science to which my invention appertains to make and use the same, reference being had to the accompanying drawings, forming a part of this specification, in which—

Figure 1 is an isometrical perspective view, and Fig. 2 a vertical section.

Like letters of reference indicate corresponding parts in both figures of the drawings.

My invention relates to means for filling bottles with lager-beer, soda, &c., when the same are provided with an automatically-closing inlet designed to be opened by the action of the bottling-machine; and it consists in an attachment or device to be used in combination with the bottling-machine, as hereinafter more fully set forth and claimed, by which such bottles may be rapidly and economically filled.

In the drawings, A represents the body, and B the nozzle, of the device, through both of which there is a corresponding central aperture, C, as shown. The body A is provided with an annular flange, d, and arranged around the nozzle there is a packing-ring, a.

As my improved device is designed as an attachment to the bottling-machines in ordinary use, a more particular description of such machines than is herein given is deemed unnecessary.

Means by which the same may be attached are shown in Fig. 2, in which E is the hollow cylindrical plunger of the machine, and K a nut for securing the same to the body A, a rabbet or shoulder being cut in the lower end of the plunger at m and properly packed to form a tight connection of the parts.

In the use of my improvement, the bottle to be filled is placed in position in the machine, (not shown,) directly under the nozzle B. The plunger is then caused to descend until the nozzle is brought into contact with the inlet mechanism or valve of the bottle, and the same is opened thereby, the aperture C registering with a corresponding aperture or opening in connection with said valve. The

liquid with which the bottle is to be filled is 55 then passed through the plunger E and nozzle B into the bottle by proper appliances for that purpose, the packing a preventing leakage, after which the plunger is elevated and the bottle removed, an unfilled one being substituted and the operation repeated.

The device herein shown is designed more especially to adapt ordinary bottling-machines for use in filling bottles provided with the improved valvular caps or stoppers for which I 65 have made an application for Letters Patent bearing even date herewith.

Having thus explained my invention, what I claim is—

1. The improved bottling-machine attachment herein described, consisting of a body, A, and a downwardly-projecting tubular nozzle, B, the device being adapted for attachment to the bottling-machine by means of a horizontal flange, d, at the upper end of the 75 body, said nozzle being adapted to open the automatically-closing inlet of the bottle, the device being provided with a central aperture, C, for the admission of the liquid, substantially as described.

2. The improved bottling-machine attachment herein described, consisting of a body, A, and a downwardly-projecting tubular nozzle, B, the upper end of the body being adapted for attachment to the bottling-machine by 85 means of a horizontal flange, d, and the lower end of said body being provided with a packing-ring, a, adapted to cushion upon the neck of the bottle and prevent leakage during filling, said nozzle being adapted to open the automatically-closing inlet of the bottle, the device being provided with a central aperture 90 for the admission of the liquid, substantially as described.

3. The combination, with the cylindrical 95 plunger of a bottling-machine, of an attachment consisting of the body A, provided with horizontal flange d at its upper end and nozzle B at its lower end, adapted to open the automatically-closing inlet of the bottle, the whole provided with a central aperture extending through the same for the admission 100 of the liquid, and a flanged nut or ring uniting said parts, substantially as described.

MARK W. PATTEN.
